CLAIM

The ornamental design for a display screen or portion thereof with a graphical user interface, as shown and described.

DESCRIPTION

The patent or application file contains at least one drawing executed in color. Copies of this patent or patent application publication with color drawings will be provided to the Office upon request and the payment of the necessary fee. FIG. 1 is a front view of a first embodiment of a display screen or portion thereof with graphical user interface, showing our new design;

FIG. 2 is a front view of a second embodiment of a display screen or portion thereof with graphical user interface, showing our new design;

FIG. 3 is a front view of a third embodiment of a display screen or portion thereof with graphical user interface, showing our new design;

FIG. 4 is a front view of a fourth embodiment of a display screen or portion thereof with graphical user interface, showing our new design;

FIG. 5 is a front view of a fifth embodiment of a display screen or portion thereof with graphical user interface, showing our new design;

FIG. 6 is a front view of a sixth embodiment of a display screen or portion thereof with graphical user interface, showing our new design;

FIG. 7 is a front view of a seventh embodiment of a display screen or portion thereof with graphical user interface, showing our new design;

FIG. 8 is a front view of an eighth embodiment of a display screen or portion thereof with graphical user interface, showing our new design;

FIG. 9 is a front view of a ninth embodiment of a display screen or portion thereof with graphical user interface, showing our new design; and,

FIG. 10 is a front view of a tenth embodiment of a display screen or portion thereof with graphical user interface, showing our new design.

The broken line showing of the display screen or portion thereof forms no part of the claimed design. The remaining broken lines show portions of the graphical user interface and form no part of the claimed design.

1 Claim, 10 Drawing Sheets
